WINDOW FRAME

Robert E. Lee, Endicott, N. Y.

Application April 17, 1952, Serial No. 282,835

2 Claims. (Cl. 20—12)

1

The present invention relates to a window frame and more particularly to a window of the type commonly employing double hung sash.

In the double hung type of window frame now in common use the stiles are provided with boxes in which run counterweights which are connected to the sashes for counterbalancing them and holding them at selected positions in the window opening. The use of counterweights requires the mounting of pulleys in the upper reaches of the stiles and the use of flexible members trained over the pulleys and connected to the counterweights and sashes. In the ordinary window frame the stiles are also provided adjacent their lower ends with access openings through which a weight is accessible for service should a flexible member to which the weight is attached become broken. Such access openings are normally closed by separate panels held in place by fastening means which frequently become so covered by paint as to render it almost impossible to remove the panel when the weight covered thereby becomes inoperative. Moreover, due to the fact that the sashes must slide freely between the stiles, the stops and the parting strips in order for the counterweights to properly function, gaps between the frame and the sashes result, and these gaps are not only not weathertight but will permit a sash to rattle in its frame.

The primary object of the present invention is to so construct a window that the sashes are not only weathertight but which will not rattle.

Another object of the present invention is to hold the sashes in selected positions in their frames without the necessity of employing counterweights, counterbalancing springs or the like.

A still further object of the present invention is to facilitate the removal of the sashes from a window frame for cleaning, glazing, repairs or for any purpose desired by the user.

The above and other objects may be attained by employing this invention which embodies among its features, shoes mounted adjacent a stile and between the stops of the frame of a double hung window for movement in a path which lies perpendicular to the stile, springs mounted between the stile and the shoes for yieldingly urging the shoes to move in said path away from the stile and means carried by the shoes and extending through the stile for holding the shoes against movement by the springs.

Other features include screws carried by the shoes and extending through the stile and strips carried and threadedly engaged by the screws

2

and bearing on the sides of the stiles remote from the shoes to form stops by which the movement of the shoes is arrested.

In the drawings:

5 Figure 1 is a rear elevational view of a window frame embodying the features of this invention.

Figure 2 is an edge view of said window frame.

Figure 3 is a horizontal sectional view taken substantially on line 3—3 of Figure 1, the upper sash being shown in slightly lowered position.

10 Figure 4 is an enlarged sectional view through the shoes and strips.

Figure 5 is a fragmentary enlarged side view of a screw, and

15 Figure 6 is a perspective view of a spring retaining ring employed to hold a screw in a shoe.

Referring to the drawing in detail a window frame designated generally 10 comprises a sill 12, a lintel 14 and stiles 16 and 18. The stile 16 is of conventional form and includes outer and inner stops 20 and 22 between which is supported a conventional parting strip 24 which defines with the stops 20 and 22 runways 26 and 28 for the outer and inner sashes 30 and 32 respectively.

20 The stile 18 is provided with outer and inner stops 34 and 36 respectively but unlike the stile 16 the space defined between the stops 34 and 36 is of somewhat greater depth than the space defined between the stops 20 and 22. Extending through the stile 18 are horizontally spaced rows of vertically spaced openings 38 and 40.

25 Mounted in the space defined between the stops 34 and 36 adjacent the stile 18 is a shoe designated generally 42 which comprises an elongated rectangular body 44 of wear resistant fiber carrying adjacent one longitudinal marginal edge an outstanding flange 46 which when the shoe is in place forms a parting strip between the sashes 30 and 32. Formed in the body 44 is a longitudinal row of openings 48 which increase in diameter as they approach the side of the body adjacent the flange 46 for the reception of supporting and guide members 50 which in the present embodiment of the invention take the form of flat headed screws. The openings 48 in the body 44 align with the openings 38 in the stile 18 so that the guide members 50 may pass through the openings 28 and enter a stop strip 52 which is disposed against the side of the stile 18 remote from the shoe 42. A compression coiled spring 54 encircles each guide member 40 between the stile 18 and the shoe 42 to exert pressure on the shoe and urge it away from the stile 18. The body 44 and flange 46 define a guideway 47 adjacent the stile 18 for the sash 32.

Mounted in the space defined between the stops 34 and 36 and the stile 18 adjacent the shoe 42 is a shoe 56 which comprises an elongated rectangular body 58 of wear resistant fibrous material which like the body 44 is provided with conical recesses 60 for the reception of supporting and guide members 62 which like the members 50 comprise flat headed screws. These supporting and guide members 62 extend through the openings 60 in the stile 18 and enter a stop grip 64 which like the stop strip 52 bears against the side of the stile 18 remote from the shoe 56. A compression coiled spring 66 encircles each supporting and guide member 62 between the stile 18 and the shoe 56 to yieldingly urge the shoe 56 away from the stile 18. Shoe 56 cooperates with the stop 34 and flange 46 in defining a guideway 68 for the sash 30.

Each supporting and guide member comprises a shank 70 which carries external screw threads 72 adjacent one end and its opposite end a flat slotted head 73 such as is commonly employed on wood screws. Fornied in the shank 70 in slightly spaced relation to its junction with the head 73 is an annular groove 74 for the reception of a spring ring 76 and the head 73 is of less thickness than that of the shoe through which the supporting and guide member extends.

In assembling the shoes 42 and 56 in a window frame embodying the features of the invention the supporting and guide members are inserted through the openings in their respective shoes and a washer 78 is placed in encircling relation to the shank 70 of its respective supporting and guide member in abutting relation to the stile 18. A spring ring 76 is then snapped into the groove 74 in abutting relation to the washer 78 to hold the head 73 in the selected opening in the shoe. It will thus be seen that the shank 70 will be retained in contact with the shoe and while being free to rotate about its axis will be held against longitudinal movement relative to the shoe. With the supporting and guide members thus assembled in the shoe 42, the springs 54 are placed in encircling relation to the shanks 70 of the members 50 and the shanks are then passed through the openings 38 in the stile 18 and threadedly engaged with the stop strip 52. The supporting and guide members 62 assembled as above described with the shoe 56 are encircled by the springs 66 and then passed through the openings 40 in the stile 18 to threadedly engage the stop strip 64. The springs 54 and 66 are preferably of the conical spiral type so that when they are fully compressed the coils thereof will lie in a common plane.

With the shoes thus assembled with the stile 18, the sash 30 may be introduced into the window frame by first entering one vertical rail of the frame thereof into the runway 68 and exerting lateral pressure thereon to move the shoe 56 against the effort of the spring 66 until the opposite side rail of the sash will pass the parting strip 24 to enter the channel 26. The effort of the springs 66 on the shoe 56 will cause the sash 30 to be pressed against the stile 16 thus holding the sash against rattling and effecting a weathertight junction between the sash and the frame. The sash 32 is entered into the runway or channel 47 and subsequently into the runway or channel 28 in a similar manner and will be held in yielding contact with the stile 16 to form a non-rattling and weathertight junction with the frame 10. By inserting the blade of a conventional screw driver into the slots in the

head 70 of the supporting and guide members and turning said members it is obvious that the pressure of the shoes on the sashes may be regulated to suit the desires of the user. By reason of the fact that the heads 72 are of less thickness than the shoes it will be obvious that no scoring of the side rails of the sashes will be experienced and because of the pressure of the shoes on the sashes, the sashes will be retained in selected positions in the runways by frictional contact with the shoes and the stile 16.

While the invention has been disclosed in connection with certain specific embodiments thereof, it is to be noted that these are by way of example rather than by way of limitations and that the invention is to be defined by the claims which should be given a scope as broad as is consistent with the prior art.

What is claimed is:

1. A window including a frame having a pair of spaced vertical stiles, spaced stops carried by the stiles, a parting strip carried by one of the stiles to form separate sash receiving channels on one side of the frame, shoes carried by the other stile to move between the stops carried thereby, a flange carried by one of the shoes and projecting perpendicularly therefrom to form a parting strip which cooperates with the stops on the second stile in defining sash receiving channels, sashes mounted in the channels to move vertically in the frame, and means disposed between the shoes and the second stile for urging the shoes against the sashes under adjustable yielding pressure, said means comprising cone shaped coil springs, flat head screws within said springs and extending through the shoes, the adjacent stile and the stops on the side of the stiles remote from the shoes.

2. A window including a frame having a pair of spaced vertical stiles, spaced stops carried by the stiles, a parting strip carried by one of the stiles to form separate sash receiving channels on one side of the frame, shoes carried by the other stile to move between the stops carried thereby, a flange carried by one of the shoes and projecting perpendicularly therefrom to form a parting strip which cooperates with the stops on the second stile in defining sash receiving channels, sashes mounted in the channels to move vertically in the frame, means disposed between the shoes and the second stile for urging the shoes against the sashes under yielding pressure, and means carried by the shoes and extending through the second stile for restricting movement of the shoes toward the sashes, said first named means consisting of cone shaped coiled springs and said second named means comprising flat head screws extending through the shoes and through the adjacent stile and threadedly engaging the stops on the side of the stiles remote from the shoes.
